METHOD OF PRODUCING SYNTHETIC FUEL

William E. Skelton, Beacon, N. Y., assignor to The Texas Company, New York, N. Y., a corporation of Delaware

Application August 10, 1944, Serial No. 548,870

8 Claims. (Cl. 260—683.4)

1

This invention relates to the manufacture of motor fuel and more particularly aviation gasoline, and is particularly directed to the production of high octane aviation gasoline of the type classed as super-fuel.

It is conventional practice to prepare so-called 100 octane aviation gasoline by blending a suitable base stock, such as straight-run or catalytically cracked naphtha of high octane, with various synthetic fuel components or additives such as C₄ alkylate and hydrogenated polymer gasoline, together with isopentane and an anti-knock compound of the character of tetraethyl lead. Where aviation gasoline of still higher performance values is required, as determined by the well known AFD-1C and AFD-3C knock rating tests, it has been necessary to include larger proportions up to substantially 100% of the synthetic fuels, thereby reducing the proportion of the base fuel permissible in the blend, and also include aromatic additives of the character of cumene to improve the rich mixture performance in supercharged engines as determined by the AFD-3C test. It has been found that isobutane-ethylene alkylate, prepared under certain critical conditions with an aluminum halide catalyst, produces a high yield of 2,3-dimethylbutane, which latter has exceptional properties for improving the AFD-3C rich mixture rating while at the same time avoiding the normal deterioration of the AFD-1C rating encountered with the aromatic additives heretofore employed. While the total C₂ alkylate can be employed as such an aviation gasoline additive with good results, it is preferred to utilize a fraction boiling up to about 265° F., or even a C₅-C₆ cut or a hexane cut which is highly concentrated in the desired 2,3-dimethylbutane.

One of the chief difficulties heretofore encountered in the design of a plant to manufacture the said C₂ alkylate additive as a component of high grade aviation gasoline or super-fuel, has been the high installation and operating expense involved in the preparation of a satisfactory ethylene feed stock for the C₂ alkylation unit. It is desirable that the ethylene feed stock should contain at least about 30% by weight of ethylene, and preferably about 40-50%, and should be comparatively free from propylene or at least have not more than about 10% by weight of propylene based on the weight of the ethylene in the charge. Also, the feed stock should contain less than about 30%, and preferably less than 25%, by weight of fixed gases lighter than C₂, namely methane and hydrogen. While re-

2

finery gases from both thermal and catalytic cracking operations are available in large quantities, the ethylene content of these gases is comparatively low, and the expense of low-temperature high-pressure fractionation to separate between ethylene and methane and form a desired ethylene charge stock has been considered economically unattractive with the equipment and methods available.

10 It has heretofore been suggested that an ethane-propane feed stock be thermally converted under high temperature and low pressure conditions to produce a resultant conversion product enriched in ethylene, which can be subsequently treated by fractionation and selective polymerization to remove propylene, to thereby produce an ethylene charge for the C₂ alkylation. This process involves expensive fractionation, and the C₃ polymer resulting from the selective polymerization is of lower grade, suitable for motor fuel but not for high grade aviation gasoline. Even in this case, the ethylene charge is diluted with a large proportion of ethane, methane and hydrogen; and the diluent gases in large proportion render the charge difficult to handle in the C₂ alkylation step, and result in substantial losses of unreacted ethylene and reduction in the yield of the C₂ alkylate.

One of the principal objects of the present invention is to provide a unitary process for producing aviation gasoline or super-fuel including C₂ alkylate as a component thereof, and wherein a purified and concentrated ethylene feed stock for the alkylation step is obtained as a component 30 part of the unitary process and in a simple and economical manner without having to fractionate between ethylene and methane.

Another object of the present invention is to provide an improved method of preparing a concentrated ethylene feed stock by a combination of petroleum oil cracking, thermal conversion of a C₃ and lighter condensate fraction of the cracking gases from the cracking step, an absorption operation for treating uncondensed products of the thermal conversion to absorb C₂ selectively from gases lighter than C₂, and a stripping operation for combined condensate from the thermal conversion and absorption condensate from the absorption operation.

40 Still another object of the present invention is to provide a unitary process of producing aviation gasoline or super-fuel involving a combination of catalytic cracking under conditions to give high gas yields and form a high grade aviation base stock, thermal conversion of C₃ and lighter

condensate gases from the catalytic cracking, recovery of a purified and concentrated ethylene feed stock low in fixed gas content from the products of thermal conversion, alkylation of the resultant ethylene feed stock to produce the 2,3-dimethylbutane additive, and catalytic conversion of C₄ constituents of the gases from catalytic cracking by alkylation or co-polymerization and hydrogenation or both, and blending of the resultant high grade products.

Another object of the invention is to provide an improved recovery and recycling system for an aluminum chloride and HCl alkylation unit, whereby both HCl and isobutane are recovered in substantial amount from the offgases in a simple and inexpensive manner for recycling to the unit.

A further object of the present invention is to provide an aviation super-fuel and an improved method of producing the same, including a blend of aviation base stock, C₂ alkylate, hydrocodimer or mixtures of hydrocodimer with C₄ alkylate, and an anti-knock agent, such as tetraethyl lead.

Other objects and advantages of the present invention will be apparent from the following description when taken in conjunction with the attached drawing and the appended claims.

As a preferred and specific embodiment, the process of the present invention involves catalytic cracking, particularly fluid catalyst cracking, of a suitable petroleum oil feed stock such as gas oil, depropanization of the resulting naphtha and lighter cracked hydrocarbon condensation products after removal of the tail gas, thermal conversion of the overhead from the depropanizing step to substantially increase the ethylene content thereof while materially reducing the C₃ content, compressing and refrigerating the compressed stream from thermal conversion to effect partial condensation with separation of uncondensed vapors from resulting condensate, passing the uncondensed vapors in contact with a C₃-C₄ absorption oil produced in a subsequent step of the process to absorb most of the ethylene and effect a separation from methane and hydrogen, passing the rich absorption oil together with the above-mentioned condensate to a fractionating step where a C₂ and lighter fraction containing at least 30 weight per cent of ethylene and less than 30 weight per cent of methane and lighter is taken overhead and thus separated from a C₃-C₄ bottoms, the major portion of the latter being returned to the absorption step to serve as the absorption oil, alkylation of the resulting C₂ and lighter fraction with isobutane under conditions to produce a C₂ alkylate consisting mainly of 2,3-dimethylbutane, debutanizing the depropanized products of catalytic cracking to separate a C₄ fraction from a stabilized cracked naphtha, subjecting the C₄ fraction to catalytic alkylation and/or co-polymerization and hydrogenation to produce C₄ alkylate or hydrocodimer or preferably both, and blending an aviation fraction of the stabilized cracked naphtha with said C₂ alkylate, said C₄ alkylate or hydrocodimer or preferably both, and with a suitable anti-knock agent, such as tetraethyl lead, to produce a resultant aviation super-fuel.

The invention is more particularly illustrated in the attached drawing which shows a preferred embodiment thereof, and wherein

Fig. 1 is a diagrammatic view of a portion of the apparatus for carrying out the method of the present invention; and

Fig. 2 is a continuation of Fig. 1 and is a dia-

grammatic view of the balance of the apparatus.

Referring to Fig. 1 of the drawing, a gas oil charge stock is introduced by the line 10 to the heating coil 11, where the temperature is raised to about 550-900° F. The heated oil then passes by line 12 to the catalytic cracking unit 13, where it is cracked in the presence of a suitable active cracking catalyst, such as a synthetic silicaluminia. It is to be understood that any conventional type of catalytic cracking can be employed, such as fixed bed, fluid catalyst, etc., although fluid catalyst cracking is preferred. It will be appreciated that the gases from catalytic cracking are more unsaturated than the corresponding gases from thermal cracking, and catalytic cracking is therefore preferred for the present process. Where the object is to produce a high grade aviation gasoline or super-fuel, the cracking step is carried out under more severe conditions to produce higher gas yields and proportionately lower motor fuel or naphtha yields, thereby forming increased quantities of ethylene and C₄ olefins which are subsequently converted to the high grade motor fuel additives. For this purpose, the fluid catalyst cracking is generally carried out at the higher temperatures of about 950-1000° F. and low pressures of the order of 5-10 pounds gauge, with a severity factor determined by the catalyst to oil ratio and the weight of oil per hour per weight of catalyst held up in the reactor to provide a conversion of 60-80% of the gas oil charged, as is well understood in this art. This will produce roughly about 15-25% by weight of total C₄ of which approximately half is butylene, about 10-15% of C₃ and lighter with the ethylene running around one-third or more of the C₂ content, and about 35-45% of 400° F. E. P. naphtha.

The resulting cracked products pass by line 14 to fractionator 15, where cycle gas oil is removed as a side stream 16, and heavier material, together with remaining suspended catalyst, is removed as bottoms by line 17 leading to a suitable filter or thickener for the recovery of the catalyst in conventional manner. It will be understood that the fluid catalyst cracking unit is merely illustrated diagrammatically, and any suitable conventional unit can be employed for this step. Moreover, it will be appreciated that the heating coil 11 need not be provided, since the oil can be heated to the desired cracking temperature by direct contact with the hot catalyst from the regenerator, as is conventional practice in certain of the fluid catalyst cracking units.

The resulting cracked naphtha together with the cracking gases pass by line 18 to condenser and cooler 19 and thence to accumulator 20, where uncondensed gas passes off by line 21. This gas is picked up by compressor 19a and forced under high pressure of the order of 200 pounds per square inch through line 11a to a conventional absorption and stripping unit indicated by 12a. Here the gas is cooled and contacted with a suitable absorption oil, such as a 34-38° gravity gas oil, to absorb a substantial proportion of the condensable gases. Unabsorbed gas, including a substantial proportion of the fixed gases, namely methane and hydrogen, and termed "tail gas," is discharged from the top of the absorber by line 13a to the refinery fuel lines. The rich absorption oil containing the absorbed gases then passes to a stripper, where the absorbed gases are stripped out of the remaining lean oil, which latter is then recycled to the absorber after being cooled. The overhead gases

are chilled and condensed to form the so-called "absorption condensate," which is returned to the system by pump 14a and line 15a.

While the tail gas of course contains some uncondensed ethylene, it is found that this separation is highly desirable in order to remove a large part of the methane and substantially all of the hydrogen from the system. This is important since the C₃ and lighter feed stock ultimately supplied to the thermal conversion unit should be relatively low in inert or fixed gases (C₁ and H₂), and preferably should run below 20 volume per cent of such fixed gases. By utilizing only the gas condensate from the cracking operation and discharging the tail gas, expensive low temperature fractionation to remove methane and hydrogen from the gas charge to the thermal conversion is avoided, thereby effecting an economical advantage in spite of some loss of ethylene in the tail gas.

The condensate from accumulator 20 is then forced by pump 22a through line 22, where it is mixed with the absorption condensate from line 15a, and the mixture passed into the pre-stabilizer or depropanizer 23 where C₃ and lighter is removed overhead by line 24. A portion of the overhead stream sufficient for reflux is diverted by line 25 through condenser 26 to accumulator 27 and returned by pump 28 and line 29 to the top of tower 23. The balance of the overhead gas which may be under line pressure of about 200 pounds per square inch at a temperature of about 100° F. is passed through a pressure reducing valve 30, where the pressure is lowered if necessary to provide an outlet pressure from the thermal conversion coil 31 of 0-50 pounds per square inch gauge. It will be appreciated that the coil inlet pressure for this condition will be dependent upon the coil design and the charge rate. The charge gas is heated to a temperature of about 1400° F. to effect cracking in the coil, and the cracked products are then rapidly cooled without allowing appreciable soaking time to prevent any substantial polymerization with the formation of normally liquid products.

Under the conditions specified above, the charge gas fed to the thermal conversion unit will generally contain about 30-40% by weight of C₂ of which at least half is ethylene, about 40-55% by weight of C₃, less than 10 weight per cent of methane with substantially no hydrogen, and a small percentage of C₄. It is desirable that this charge gas be as high in ethylene content as practicable, since the ethylene appears to pass through the cracking coil substantially unchanged. Therefore, the depropanizer overhead from the catalytic cracking condensate represents a very suitable charge stock to the gas conversion step, since it is higher in initial ethylene content than the comparable C₃ and lighter fraction obtained from the condensate of thermal cracking, and is much higher in ethylene content and much lower in methane and hydrogen content than the C₃ and lighter gases from either catalytic or thermal cracking from which the tail gas has not been separated. The propane-propylene ratio of the charge gas appears relatively unimportant, since both of these constituents are susceptible to cracking to ethylene in about equal degree. Some of the ethane of the charge gas of course breaks down with the formation of ethylene and lighter; but additional ethane is formed in the gas conversion step from the cracking of propane and propylene. Consequently, the ethane content of the products of

gas conversion may be roughly about the same as that of the charge gas. The C₄ content of the charge gas should of course be as low as practicable as these constituents are more useful for other purposes as hereinafter described.

The net result of the thermal conversion treatment under the conditions specified is to substantially decrease the C₃ content of the charge gas, while at the same time increasing the ethylene, methane, and hydrogen content thereof with little or no increase of the ethane content. Also, there is a very small build-up to C₄ and heavier. The inevitable breakdown to methane and hydrogen under these conditions is not objectionable since the charge gas had been largely denuded of these constituents and the resultant products of conversion will therefore contain less than about 25% by weight of methane and hydrogen. This proportion of the lighter or fixed gases can readily be tolerated in the subsequent absorption step without objectionable loss of ethylene. Such is not the case where the fixed gas content of the products of conversion is higher, since the sweeping effect of higher proportions of these fixed gases acts to entrain ethylene in the off-gas from the absorption step with correspondingly greater loss of the desirable ethylene.

The conversion products from cracking coil 31 are passed by line 32 to exchanger 33 containing heating coil 34 connected to waste heat boiler 35. Boiler feed water is supplied by line 36 and passes through the heat exchange coil 34, whereby the waste heat of the conversion products is used to generate high pressure steam, such as steam of 150 pounds per square inch gauge, and the conversion products are thereby rapidly cooled below a reaction temperature. The resulting gaseous products of thermal conversion, which may thereby be cooled from 1400° F. to around 600° F., thence pass by line 37 through water cooler 38 where they are further cooled to about 110° F. The gases are then fed by line 39 to a compressor 40, where they are compressed to about 500 pounds per square inch, and thence are supplied to exchanger 41 where they are refrigerated to about 0° F. with refrigerant supplied by line 42 at about -20° F. The resultant compressed and refrigerated products are then introduced by line 43 into accumulator 44, where vapor-liquid separation is made. This condensation substantially reduces the load on the absorber and materially improves the ethylene recovery in the absorption step.

The uncondensed gases from accumulator 44 pass by overhead vapor line 45 to absorber 46, which latter is supplied with a lean absorption oil by line 47. As will be more particularly described hereinafter, the absorption oil is preferably a C₃-C₄ bottoms obtained from the conversion products, and therefore supplied by the system. The heat of absorption is continuously removed by circulating condensate from an intermediate tray of the absorber by line 48 through exchanger 49 supplied with refrigerant at about -20° F. by line 50 and returned by pump 51 and line 52 to a lower tray of the absorber. By the use of this intercooler, the temperature of the absorber is maintained at about 0° F.; and under the high pressure it is possible to recover up to about 94-96% by weight of the ethylene in the gas supplied to the absorber by line 45. There is a selective action of the C₃-C₄ absorption oil as between the ethylene and ethane on the one hand, and methane and hydrogen on the other, whereby

a substantial proportion of the methane and most of the hydrogen can be removed by overhead line 54 through pressure release valve 55 as tail gas which can be sent to the gas fuel lines. The net result is a recovery of a C₂ and lighter product gas in the absorber containing about 40 weight per cent of ethylene for an overall recovery of about 94% of the ethylene in the gas supplied to the absorber by line 45. By somewhat reducing the percentage of overall ethylene recovery down to say 85%, a product gas will be absorbed containing as high as 50 weight per cent or more of ethylene in the C₂ and lighter portion.

The rich absorption oil passes from absorber 46 by bottom line 57 and is mixed with a stream of condensate passing from the bottom of accumulator 44 by line 58. The mixed stream then flows through pressure reducing valve 59 where the pressure is reduced to about 400 pounds per square inch, and is introduced into fractionator 60. The latter is operated under conditions to separate between C₂ and C₃, taking overhead material containing less than about 3% by weight of C₃. At a pressure of 400 pounds per square inch, a top tower temperature of about 0° F. with a bottom tower temperature of about 160-165° F. in a 25-tray tower will accomplish the desired separation. The bottom tower temperature is maintained by a reboiler 61 through which liquid bottoms of the tower are circulated by coil 62, and to which high pressure steam is supplied from the waste heat boiler 35 by line 63 and branch line 64.

The C₂ and lighter overhead from fractionator 60 passes by line 65 through exchanger 66 supplied with refrigerant at about -20° F. by line 67, the chilled overhead then flowing by line 68 to accumulator 69 where sufficient liquid is condensed to supply the reflux requirements of tower 60, said reflux being returned to the tower by pump 70 and line 71.

Lean oil accumulating in the bottom of fractionator 60, and which consists essentially of C₃-C₄ hydrocarbons with the C₃ amounting to at least about 80% by weight thereof, is discharged by line 72. A major proportion thereof is recirculated by pump 73 and line 74 through water cooler 75 and then through exchanger 76 supplied with refrigerant at about -20° F. by line 77, and the refrigerated lean oil then passes by line 47 to the top of the absorber to serve as the absorption oil therein. It is thus seen that the bottoms heavier than C₂ from the gas conversion unit 31 is utilized as the absorption oil, so that absorption oil from an extraneous source is not required. Moreover, sufficient makeup C₃-C₄ is continuously formed and supplied from the conversion unit 31, so that the absorption oil in the system is continuously replenished, while some excess is continuously discharged from the system. This excess flows through line 78, and all or any portion thereof may be recycled by line 79 to the inlet of the conversion coil 31 for recracking.

Since the high temperature employed in the conversion unit 31 produces a small amount of aromatics, a portion of the excess bottoms is continuously or intermittently diverted by line 80 through heater 81, where the temperature is raised to about 400-500° F. The heated C₃-C₄ highly unsaturated charge then passes through polymerization unit 82, which may be of the fixed bed phosphoric acid type, where the olefins are polymerized to form polymer gasoline for motor

fuel. Products of polymerization are passed by line 83 to depropanizer 84, where C₃ and any lighter is removed overhead and returned by line 85 to the recycle line 79 for return of this material to the thermal conversion unit 31. In this manner, heavier aromatics are removed from the absorption-stripping system to prevent build-up therein, while at the same time a yield of polymer gasoline for motor fuel is obtained and unpolymerized paraffin gases recovered and recycled to the thermal conversion unit. The depropanized polymer gasoline is discharged from tower 84 by line 86 leading to a suitable stabilizer and thence to storage (not shown).

Uncondensed C₂ and lighter is removed from accumulator 69 by line 87 together with any excess condensate over that required as reflux for tower 60 and which is removed by liquid line 88. The resulting concentrated and purified ethylene charge then passes through pressure reducing valve 89, where the pressure is reduced to about 250-300 pounds per square inch as desired for passage through the C₂ alkylation unit hereinafter described. The charge then passes by line 90 through product heater 91 supplied with high pressure steam from waste heat boiler 35 by line 63 and branch line 92 to compensate for the heat of expansion and to raise the temperature of the charge to about 110-130° F. The purified ethylene charge at the proper pressure and temperature then passes by line 93 to the C₂ alkylation unit as more particularly described in connection with Fig. 2.

Referring again to the depropanizer 23, the catalytically cracked naphtha bottoms from that tower is passed by line 95 to the debutanizer 96 which is operated to remove C₄ overhead by line 97. The stabilized cracked naphtha then passes by line 98 to the fractionator 99 where the desired aviation fraction is removed overhead by line 100 through condenser 101 to accumulator 102. Aviation naphtha base stock is then drawn from this accumulator and passed by line 103 to the blending tank for the preparation of finished aviation gasoline, as more particularly described hereinafter in connection with Fig. 2. The heavy naphtha bottoms from fractionator 99 are withdrawn by line 104 to storage for motor fuel.

The overhead C₄ fraction from line 97, which contains a high proportion of butylenes in addition to isobutane and normal butane, is passed all or in part by line 105 to the C₄ alkylation unit 106, where the butylenes are alkylated in conventional manner with isobutane introduced by line 107 in the presence of a suitable alkylation catalyst, preferably strong sulfuric acid or hydrofluoric acid, introduced by line 108. As the conditions for butylene alkylation are well-known and any conventional type of alkylation unit, such as the pump and time tank, jet reactor or impeller reactor, together with customary neutralizing, washing and fractionating equipment, can be employed, no further description of this step is required. A debutanized 311 to 350° F. end point fraction of the C₄ alkylate is passed by line 109 to the blending tank described in connection with Fig. 2.

On the other hand, all or any part of the C₄ fraction from line 97 may be passed by branch line 110 to the C₄ copolymerization unit 111, where isobutylene and normal butylene are copolymerized in conventional and well-known manner. The resulting codimer or fraction thereof boiling up to about 265° F. is then passed by line 112 to a hydrogenation unit 113 to saturate the product

and form hydrocodimer in conventional manner. The resulting hydrocodimer is supplied by line 114 to the blending tank described in connection with Fig. 2.

The proportions of the C₄ fraction from line 97 supplied to C₄ alkylation and to hydrocodimer production respectively depend upon the isobutane and butylene balance of the particular refinery as well as upon the ultimate grade of aviation gasoline desired. Both the C₂ alkylation and the C₄ alkylation require substantial amounts of isobutane. Where the isobutane supply is limiting, and there is an over-supply of butylenes in relation to isobutane required for C₂ alkylation and C₄ alkylation, then a part or all of the C₄ may be passed to hydrocodimer production, with provision for the recovery of the isobutane in the charge supplied thereto by line 110, so that this isobutane can be used for C₂ alkylation. Where there is a plentiful supply of isobutane and maximum capacity of aviation alkylate is desired, then all or substantially all of the C₄ from line 97 will be passed to C₄ alkylation. However, where the object is to produce a high grade super-fuel, and quality rather than quantity of the aviation gasoline is controlling, the C₄ charge will generally be split between the C₄ alkylation unit and the hydrocodimer unit to provide both types of high grade aviation components for blending with the C₂ alkylate and the catalytically cracked base stock in the manner hereinafter described.

Referring to Fig. 2, the purified and concentrated ethylene charge from line 93 passes by line 116 together with fresh feed isobutane from line 117 and recycle isobutane from line 118 to the surge tank 119. From here, the charge passes by line 120 and either of valve controlled branch lines 121 and 122 to one of a pair of dehydration tanks 123 and 124. These tanks are preferably filled with activated alumina or other suitable dehydrating agent which serves to remove moisture from the hydrocarbon charge to the C₂ alkylation unit. The dehydrated charge then flows by either of branch lines 125 and 126 to line 127, which in turn connects with line 128 leading to the alkylation reactor. Dehydrating tanks 123 and 124 are operated alternately, one being on stream for drying the charge while the other is being reactivated by heated fuel gas or air supplied by line 130 containing steam heater 131 and connected by valve controlled branches 132 and 133 with tanks 123 and 124 respectively. The reactivating gas is discharged from the tanks by either of branch lines 134 and 135 to line 136 containing water cooler 137, and leading to water settler 138. Water removed from the dehydrating bed by the reactivating gas is thus separated from that gas in 138 and discharged by line 139 to suitable disposal, while the reactivating gas is then passed by line 140 to a suitable holder for ultimate return to line 130 and recirculation in the system.

The C₂ alkylation reactor 142 is preferably of the tower type as described and claimed in the pending application of Louis A. Clarke, Serial No. 535,261, filed May 12, 1944, now Patent No. 2,407,137 dated September 3, 1946, and the conditions of the reaction are as described in that application. For example, tower 142 may be six feet in diameter and 70 feet in height and is filled nearly to the top with an aluminum chloride-hydrocarbon complex liquid activated by the addition of dispersed aluminum chloride. This complex liquid may be prepared by heating kerosene, naphtha, or an alkyl chloride such as tertiary

butyl chloride, with aluminum chloride until a liquid product is formed as the result of a combination or complexing of the aluminum chloride with the hydrocarbon or alkyl chloride. Kerosene is generally used to initially form the complex liquid for starting up the plant, and thereafter the necessary makeup complex liquid is supplied in situ by reaction of alkylate with dispersed aluminum chloride. To the preformed complex liquid there is added a quantity of anhydrous aluminum chloride which is dispersed in the complex liquid and activates the same. During continuance of the process, additional aluminum chloride is added by line 143 to maintain the activity of the catalyst, as generally controlled by measurement of the heat of hydrolysis which should be maintained above about 320 calories per gram of activated complex liquid.

The activated aluminum chloride-hydrocarbon complex liquid is maintained as the continuous phase in the tower and the isobutane-ethylene charge together with a small proportion of HCl introduced by line 144A in a proportion to provide less than 0.1% by weight on the weight of the hydrocarbon charge, are passed through line 144 and dispersed through a plurality of nozzles or orifices 145 into the liquid catalyst body adjacent the base of the tower. As heretofore described, the pressure on the tower is maintained at around 225 pounds per square inch so that the isobutane, which is used in substantial molar excess of the ethylene, is in liquid phase. The ethylene feed however may be in gas phase, being effectively mixed and dispersed in the isobutane from lines 117 and 118 and isobutane recycle from line 146, and also hydrocarbon or alkylate liquid recycle from line 147. The mixed phase feed at a temperature of about 110-130° F. is thereby dispersed in the form of a multitude of small droplets into the complex catalyst liquid; and these droplets rise upwardly through the catalyst liquid due to difference in gravity therebetween and without sufficient agitation to form an emulsion, until they reach the upper surface thereof, when the liquid hydrocarbon constituents coalesce to form a superposed hydrocarbon layer at the top of the tower.

With an ethylene charge gas containing at least about 30 weight per cent ethylene, the balance being mainly ethane and methane, and using an isobutane to ethylene mol ratio of about 4-5:1 and a ratio of hydrocarbon recycle from line 147 to fresh feed of about 10-20:1 by volume, it is found that at least about 80-85% by weight of the ethylene in the charge gas can be efficiently reacted or alkylated to produce a high grade alkylate consisting mainly of 2,3-dimethylbutane. The superposed hydrocarbon layer together with unreacted gas consisting of the residual ethylene in addition to the ethane, methane and HCl, pass by overflow line 148 to gas separator 149, where gas and liquid separation takes place. The gas is removed by line 150 to a scrubber 151 which may be supplied with a caustic solution or lime slurry by line 152 to neutralize the HCl, the water solution of the resulting chloride salt being removed through the bottom drain 153. The off-gas, which also contains a substantial proportion of isobutane, is then passed by line 154 to an absorber 155 supplied with a suitable absorption oil, such as a 36-38 gravity gas oil, by line 156. The absorber is cooled by recirculation from an intermediate tray through line 157 passing through water cooler 158 and returned by line 159 to a lower tray. The absorption oil serves to selectively remove most

of the isobutane from the gas, which latter is discharged by overhead line 160 to fuel, or may be recycled to the inlet of the conversion heater 31 as illustrated in Fig. 1. It will be understood that the above described recovery and recycling process is generally applicable to any isoparaffin alkylation process employing aluminum chloride and HCl as the catalyst, and particularly a mixed phase process where both HCl and isobutane are present in offgases from the alkylation unit.

The enriched absorption oil passes by line 162 through steam heater 163 into the upper portion of stripper 164. Live steam is introduced into the bottom of the stripper by line 165 and serves to strip out the absorbed isobutane. The lean absorption oil is returned from the bottom of the stripper by pump 166 through water cooler 167 and thence by line 156 to the absorber 155. Overhead vapors of water and isobutane pass from stripper 164 by line 168 through water cooled condenser 169 to separator 170, where separate layers of condensed water and isobutane form. The lower water layer is discharged to ditch by line 171. The upper isobutane layer is returned by line 172, pump 173 and line 118 to form a portion of the recycle isobutane for the C₂ alkylation unit. As this recycle isobutane is mixed with the ethylene charge in advance of the dehydration unit, any remaining water is thereby effectively removed.

When it is desired to recover the HCl in the off-gas of line 150 for recycling to the alkylation unit, an alternative procedure is employed in scrubber 151. In place of supplying an alkaline solution to the scrubber by line 152, a constant boiling mixture of water and HCl is substituted, containing approximately 11 mol per cent HCl and 89 mol per cent H₂O. Contact of this constant boiling mixture with the vapors in scrubber 151 dissolves or absorbs the HCl. The enriched HCl solution discharged by bottom line 153 is then passed by line 150a to a distillation tower 151a containing a closed coil heater 152a. The excess HCl is removed overhead by line 153a, dried in a suitable sulfuric acid or alumina drier 154a, and recycled by line 155a to line 144. The constant boiling mixture of HCl and water discharged as bottoms by line 156a from the distillation unit is passed through a suitable cooler 157a and then recycled by line 158a and line 152 to the scrubber 151. Depending upon the percentage of HCl employed in the hydrocarbon charge to the alkylation unit, the expense of recovering and recycling the HCl may be less than the expense of the fresh HCl and neutralizing agent required in the first described procedure, in which event the HCl recovery system is used. Ordinarily, where proportions of HCl less than about 0.05% by weight of the hydrocarbon charge are employed, the HCl recovery system is not economically justified and the neutralization procedure is used.

The hydrocarbon liquid layer in gas separator 149, in which some of the complex catalyst may be entrained, passes by line 175 to settler 176 where the liquid complex catalyst immediately drops out and is returned by gravity through line 177 to the continuous catalyst phase within tower 142. Excess complex liquid formed in situ in the tower 142 during continuance of the process is discharged intermittently or continuously at a low rate by bottom line 178. This also serves to prevent the thickening or increase in viscosity of the complex liquid which would otherwise occur during long periods of continuous operation,

thereby maintaining the proper fluidity of the catalyst. The supply of fresh aluminum chloride, which may be conveniently accomplished by feeding in a slurry or suspension of powdered aluminum chloride in a small amount of complex liquid by line 143, effectively maintains the activity of the catalyst during continuous operation.

The hydrocarbon layer from settler 176 is discharged by line 180, and the major proportion thereof is diverted to line 181 through water cooler 182, and thence recycled by line 147 and pump 183 for mixing with the fresh hydrocarbon charge from line 127 and recycle isobutane from line 146, the mixture passing through line 128 to the dispersion nozzles 145 in the base of tower 142 as previously described. This hydrocarbon recycle thus serves to maintain the proper reaction temperature within the alkylation tower, as well as to supply a substantial volume of liquid for mixing with the gas phase of the hydrocarbon charge, thereby producing more effective dispersion and reaction of the ethylene in the mixed phase operation. A minor proportion of the hydrocarbon product from line 180 is discharged by line 185 to the deisobutanizer 186 equipped with reboiler 187 and operated under conditions to remove overhead an isobutane-rich stream containing up to 95% or more of isobutane. This isobutane stream passes through condenser 188 and line 189 to accumulator 190, from which pump 191 returns a portion thereof through line 192 to serve as reflux for the tower, the balance being recycled by line 146 to the alkylation charge line 128 as heretofore described.

The bottoms from tower 186 are passed by line 194 and pump 195 to debutanizer 196 equipped with reboiler 197 and operated under conditions to remove remaining C₄ overhead. This vaporized normal butane passes through condenser 198 and line 199 to accumulator 200, from which pump 201 returns a portion as reflux by line 202 to the tower 196, the balance being discharged by line 203 to butane storage to serve as a charge stock for isomerization where such facilities are available and additional isobutane is required, or for other suitable use.

The debutanized alkylate passes by line 205 to pump 206, the latter forcing the charge through a heating coil 207 where the temperature is raised to about 300 to 650° F. and preferably about 500° F. The heated alkylate then flows by line 208 through either of valve controlled branch lines 209 and 210 into one of the clay treating chambers 211 and 212. These chambers are filled with a suitable percolation clay, such as fuller's earth, which serves to remove combined chlorine from the heated alkylate. This chloride removal materially improves the lead susceptibility and other desirable properties of the alkylate.

The resulting chloride-free alkylate then passes by one of valve controlled branch lines 213 and 214 to line 215, which latter introduces the same into alkylate fractionator 216. The percolation clay chambers are employed alternately, so that one may be replaced with fresh clay while the other is on stream. Fractionator 216 is equipped with reboiler 217 and is operated to take overhead a desired aviation fraction, preferably the fraction boiling up to about 265° F. As previously described, the total debutanized C₂ alkylate produced under the conditions specified consists largely of 2,3-dimethylbutane. For example, the C₆ content of this alkylate which is mainly 2,3-dimethylbutane may run about 75-85 volume per

cent, with the C₅ content being less than 5 volume per cent, and the C₇-C₈ content running about 10-15 volume per cent. The bottoms boiling above 265° F. will also generally run less than about 5 volume per cent. Consequently, the debutanized 265° F. end point alkylate fraction constitutes a very satisfactory aviation fuel additive to provide the rich mixture performance and other desirable characteristics of 2,3-dimethylbutane. If desired, the cut point on the fractionator 216 can be at the initial boiling point of the C₇ fraction to take overhead a C₅-C₆ material; and the latter can be further fractionated to separate a total hexane cut or a material consisting almost entirely of 2,3-dimethylbutane.

The overhead aviation cut from fractionator 216 passes through condenser 218 and line 219 to accumulator 220 from which pump 221 returns a portion as reflux to tower 216 by line 222. The bottoms from tower 216 are passed by pump 223 through cooler 224 and line 225 to storage for motor fuel.

The desired proportion of the aviation fraction of the C₂ alkylate is withdrawn from accumulator 220 by pump 226 and passed by line 227 to blending tank 228. Suitable proportions of the C₄ alkylate, catalytically cracked base stock and hydrocodimer, produced as described in connection with Fig. 1, may also be introduced into the blending tank 228 by lines 109, 103 and 114 respectively. In some cases, a high octane straight run aviation naphtha introduced by line 229 may be used in conjunction with or in substitution for the catalytically cracked base stock. In addition, the desired amount of anti-knock agent such as tetraethyl lead may be added by line 230, and commercial isopentane may be added by line 231. The resulting blended aviation gasoline is discharged by line 232 to suitable storage. It will be understood that the aviation base stock, either catalytically cracked or straight run, or certain selected fractions thereof, can be acid treated or subjected to catalytic rerunning in conventional manner prior to introduction into blending tank 228. It will also be understood that a gum inhibitor may be added to the blend, particularly one made from the catalytically cracked base stock; and any other agents, such as dyes, color stabilizers, etc. included in well known manner.

The following specific example is given as illustratory of the present invention, but it is to be understood that the invention is not limited thereto.

A 31.7 gravity paraffinic gas oil having a 50% evaporated point at 675° F. was subjected to fluid catalyst cracking with a synthetic silica-alumina cracking catalyst, resulting in a 65% conversion under the following conditions:

Temperature, °F. 975
Pressure pounds per square inch gauge 5-10
Catalyst/oil weight ratio 4.5
Weight of oil per hour per weight of catalyst held up in reactor 1.0

The conversion products resulting from this operation analyzed as follows, based on the gas oil charged:

	Per cent
C ₃ and lighter dry gas	weight
Coke	do
Total C ₄	volume
C ₅ -400° F. end point naphtha	do
Cycle gas oil	do

The depropanizer overhead resulting from de-

propanization of the combined catalytically cracked naphtha condensate and the absorption condensate in depropanizer 23 (Fig. 1), and supplied as feed stock to the gas conversion unit 31, has the following typical analysis:

	Weight per cent
Hydrogen	0.0
Methane	6.0
Ethylene	12.9
Ethane	24.2
Propylene	14.5
Propane	39.6
C ₄ plus	2.8

15 A typical analysis of the conversion products from unit 31, obtained with the feed set forth immediately above, is the following:

	Weight per cent
20 Hydrogen	0.5
Methane	21.9
Ethylene	30.0
Ethane	26.6
Propylene	9.0
25 Propane	7.3
C ₄ plus	4.7

30 With an overall recovery of 94% of the ethylene in the absorber-fractionator system 46-60, the product gas supplied by line 93 to the C₂ alkylation unit analyzes as follows:

	Weight per cent
Hydrogen	0.2
35 Methane	21.9
Ethylene	41.5
Ethane	35.9
C ₃	0.5

40 The following tabulation is a summary of the utilities required for producing 110,000 pounds of ethylene per stream day:

	Steam, Lbs./Hr.	Power, KWH./Hr.	Cooling Water, G./M.	Fuel, Bbls./Hr.
Heater				
Gas Compressor				
Waste Heat				
50 Boiler (8,060)				
Cracked Gas Cooler				
Refrigeration	770		378	
Pumping	20			
Reboiler	5,880			
Product Heater	2,700			
55 Net Total	520	700	3,830	7.02

The 8,060 pounds of steam per hour enclosed in parenthesis in the above table represents a net production in the waste heat boiler 35, which substantially supplies the steam requirements of the plant, leaving only a net total of 520 pounds per hour to be furnished from an exterior source. The fuel requirements are readily met by the tail gas and other gases discharged to the fuel lines. The major requirement for cooling water is readily obtained at low cost, and the actual refrigeration requirements are low. It is therefore seen that the operating expense of the present method is extremely low in comparison with the utilities required for conventional low-temperature high-pressure fractionation, and a very economical system is thereby presented.

The conditions of the C₂ alkylation operation and the results obtained, utilizing the concen-

15

trated and purified ethylene charge gas set forth above, are listed in the following table:

Reactor temperature, °F	4/1
Reactor pressure pounds per square inch	110
Isobutane/olefin mol ratio	275
Catalyst life	16 gallons alkylate per pound of aluminum chloride minimum
Promoter	0.1% by weight based on total hydrocarbon charge minimum
Alkylate yield weight per cent ethylene reacted	262
Ethylene reacted, weight per cent of ethylene charged	81

16

ene mol ratio in the reactor, with a 67 volume per cent conversion to codimer based on the butylenes converted, and with a 93% total butylene conversion. The polymerization products were fractionated to separate a codimer fraction boiling up to about 270° F. This fraction was then hydrogenated in the hydrogenation unit 113 in conventional manner in the presence of Raney nickel at a temperature of about 450° F. and a pressure of about 1000 pounds per square inch to saturate the codimer and produce the so-called hydrocodimer.

Typical tests on the resulting C₂ alkylate, C₄ alkylate, hydrocodimer and the catalytically cracked base stock produced as described above, together with the same tests on a straight run aviation base stock supplied from an exterior source, are set forth in the following table:

	C ₂ alkylate of approximately 75% 2,3-dimethylbutane	C ₄ alkylate	Hydrocodimer	Catalytically cracked base stock	Straight run base stock
Gr., °API	81.0	70.0	66.4	54.3	62.0
RVP, p. s. i.	7.6	3.0	2.7	6.5	6.7
ASTM Distillation:

C ₆	80
C ₇ -C ₈	13
265° F.	40

On the basis of 1000 barrels per stream day of alkylate, the isobutane and ethylene requirements are:

Isobutane consumed in alkylate reaction	BPSD	730
Ethylene charged to reactor	lbs./SD	109,830
Ethylene consumed	lbs./SD	88,962

The C₄ olefinic feed charged by line 105 to the C₄ alkylation unit 106 was alkylated under conventional conditions in a pump and time tank reactor at a temperature of around 50° F., utilizing a 5/1 isobutane to butylene feed ratio, a 150/1 isobutane to olefin contact ratio in the reactor due to emulsion recycle, a 60% isobutane concentration in the reacted mix, a contact time of 30 minutes, a pressure of about 50 pounds to maintain the reactants in liquid phase, and makeup fresh feed of sulfuric acid of 98% strength to maintain a titratable acidity within the reactor system of about 89-90% H₂SO₄. The resulting alkylate products were neutralized, washed, and fractionated in conventional manner, and a 310° F. end point aviation alkylate fraction separated.

The portion of the C₄ feed supplied by line 110 to the C₄ copolymerization unit 111 was treated under conventional conditions at a temperature of about 320-345° F. in the presence of a fixed bed phosphoric acid catalyst, utilizing recycle to maintain about a 2:1 normal butylene to isobutyl-

The invention is further illustrated in the following table showing typical blends of the stocks listed above, together with commercial isopentane, to produce a "120/150" grade aviation fuel, which is classed as a superfuel. The "120/150" refers to Army and Navy performance numbers, the 120 performance number being a 1C rating of iso-octane plus 0.69 ml. TEL per gallon or a 1C index number of 106; and the performance number of 150 being a 3C rating equivalent to S reference fuel 3.55 ml. TEL/gal. or a 3C index number of 152. The table is based on the preparation of 100 barrels of this grade of aviation fuel containing 4 cc. TEL/gal.

Components, bbls.	C ₂ alkylate+hydrocodimer	C ₂ alkylate+C ₄ alkylate	C ₂ alkylate+C ₄ alkylate+hydrocodimer
Isopentane	11.9	8.4	16.1
C ₂ alkylate	41.6	50.0	25.0
C ₄ alkylate		29.1	14.5
Hydrocodimer	38.1		38.1
Aviation base stock	8.4	12.5	6.3
Isobutane required, bbls.	31.4	56.8	38.4

The aviation base stock set forth in the above table can be either the catalytically cracked base stock or the straight run base stock listed in the preceding table, since the properties of the two base stocks are similar except for 3C octane and the proportions used are small, with the result that little difference occurs in the calculations for the above blends with either base stock. The above table demonstrates that the smallest isobutane requirement for the production of this superfuel is in the blend of C₂ alkylate with hydrocodimer. The largest isobutane requirement is in the blend of C₂ alkylate and C₄ alkylate, but in this case a higher proportion of the base stock

is permissible. Consequently, where isobutane is available, while isopentane is limited, this represents a desirable blend. For maximum production of this grade of aviation fuel with a relatively small but intermediate isobutane requirement and a minimum amount of C₂ alkylate, the blend containing both C₄ alkylate and hydrocodimer with the C₂ alkylate is preferred.

It is obvious that various grades of aviation super-fuel can be produced by the method of the present invention, the above examples being merely illustratory. Furthermore, while certain specific temperature and pressure conditions have been set forth above for the C₃ and lighter thermal conversion, it is to be understood that these conditions can be varied from the specified preferred operating conditions. For example, temperatures of about 1250 to 1500° F. can be employed with pressures ranging from about atmospheric up to about 500 pounds per square inch or somewhat higher. Also the specified conditions for the absorption and stripping operations for recovering the ethylene feed stock to the C₂ alkylation unit are merely the preferred conditions for economical operation, and the temperature and pressure conditions can be varied from those shown and coordinated to give similar results as will be well understood in this art.

While an activated aluminum chloride-hydrocarbon complex catalyst has been described above as being preferred for the C₂ alkylation, it is to be understood that other aluminum halide catalysts can be employed for this purpose. For example, other aluminum halide, such as aluminum bromide, complex liquids activated by the addition of aluminum halide may be used. Likewise, a fixed bed operation with lump aluminum chloride, or a bed of inert contact material impregnated with aluminum halide may be employed. Likewise, in the C₄ alkylation, while sulfuric acid or hydrofluoric acid are preferred as catalysts, other well-known catalysts for this reaction can be used, such as BF₃-water complex, chlorosulfonic acid and the like. The copolymer can also be produced with other conventional catalysts such as sulfuric acid, phosphoric acid and the like, as is well understood; and the hydrogenation of the copolymer can be carried out in well-known manner with other conventional hydrogenation catalysts including metal sulfides and oxides.

As set forth above, condensate from catalytic cracking is preferred because of the higher olefinic content. Moreover, catalytic cracking is capable of producing a high grade aviation base stock, which is not the case with the naphtha produced by thermal cracking. However, where a sufficient supply of high grade straight run aviation base stock is available, thermal cracking condensate including absorption condensate, from which tail gas has been separated, can be utilized as a part or all of the charge to the thermal conversion unit in accordance with the present invention. In such case the thermal conversion may be carried out under somewhat more severe conditions to increase the ethylene content, and the absorption step is generally operated with a lower net ethylene recovery so as to effect the desired separation of methane and hydrogen and obtain a C₂ charge for alkylation which is sufficiently concentrated in ethylene. The present invention thus enables such thermal cracking condensate to be utilized as a charge for the process with somewhat lower alkylate yield on the basis of the gas condensate handled. This is feasible for a refinery which is not provided with catalytic cracking facilities

but has a sufficient supply of cracked gases from thermal conversion operations and also a source of supply of straight run aviation base stock.

Further, it is to be understood that a portion of thermal cracking condensate can be mixed with catalytic cracking condensate for purposes of the present invention. This is particularly suitable in those cases where the catalytic cracking produces an excess of aviation base stock over the required amount of C₂ and C₄ alkylates as well as hydrocodimer. By mixing a portion of the thermal cracking condensate with the catalytic cracking condensate, the supply of ethylene and butylenes can be increased to provide a refinery balance, and thus utilize the products produced by the present process to the best advantage in the production of maximum quantities of the aviation superfuel.

Obviously many modifications and variations of the invention, as hereinbefore set forth, may be made without departing from the spirit and scope thereof, and therefore only such limitations should be imposed as are indicated in the appended claims.

I claim:

- 25 1. The method in the manufacture of high octane aviation gasoline which comprises recovering from the products of cracking of hydrocarbon oil a C₄ fraction containing butylenes and a C₃ and lighter condensate fraction containing a substantial proportion of ethylene and some methane, subjecting the said C₃ and lighter condensate fraction to thermal conversion at high temperature and low pressure to substantially increase the ethylene content thereof while materially reducing the C₃ content, recovering from the products of thermal conversion by condensation and absorption most of the ethylene content of said conversion products in a refrigerated condensate, fractionating said last-mentioned condensate at a pressure substantially below that required to fractionate between ethylene and methane to separate a C₂ and lighter fraction containing at least 30% by volume of ethylene and less than 25% by volume of methane and hydrogen, alkylating isobutane with ethylene of the said C₂ and lighter fraction in the presence of an aluminum halide catalyst under alkylating conditions to produce a C₂ alkylate consisting mainly of 2,3-dimethyl-butane, dividing said C₄ fraction into two portions, subjecting one portion of said C₄ fraction to polymerization and hydrogenation to form hydrocodimer from the butylene content thereof, alkylating isobutane with the other portion of said C₄ fraction in the presence of an acid alkylation catalyst to produce C₄ alkylate, and blending an aviation base stock with said C₂ alkylate, said hydrocodimer, said C₄ alkylate and isopentane to form high octane aviation gasoline.
- 30 2. The method in the recovery from the products of cracking of hydrocarbon oil of a fraction lighter than C₃ containing a high proportion of ethylene, which comprises subjecting the cracked hydrocarbon oil products to cooling and condensation to form a condensate consisting of cracked naphtha together with lighter normally gaseous hydrocarbons, separating uncondensed normally gaseous hydrocarbons from said condensate, subjecting said separate normally gaseous hydrocarbons to absorption with an absorption oil to absorb a portion of the said gases while the remainder passes off as tail gas, stripping the rich absorption oil to remove the absorbed normally gaseous hydrocarbons and cooling the latter to recover an absorption condensate, combining the
- 35 3. The method in the manufacture of high octane aviation gasoline which comprises recovering from the products of cracking of hydrocarbon oil a C₄ fraction containing butylenes and a C₃ and lighter condensate fraction containing a substantial proportion of ethylene and some methane, subjecting the said C₃ and lighter condensate fraction to thermal conversion at high temperature and low pressure to substantially increase the ethylene content thereof while materially reducing the C₃ content, recovering from the products of thermal conversion by condensation and absorption most of the ethylene content of said conversion products in a refrigerated condensate, fractionating said last-mentioned condensate at a pressure substantially below that required to fractionate between ethylene and methane to separate a C₂ and lighter fraction containing at least 30% by volume of ethylene and less than 25% by volume of methane and hydrogen, alkylating isobutane with ethylene of the said C₂ and lighter fraction in the presence of an aluminum halide catalyst under alkylating conditions to produce a C₂ alkylate consisting mainly of 2,3-dimethyl-butane, dividing said C₄ fraction into two portions, subjecting one portion of said C₄ fraction to polymerization and hydrogenation to form hydrocodimer from the butylene content thereof, alkylating isobutane with the other portion of said C₄ fraction in the presence of an acid alkylation catalyst to produce C₄ alkylate, and blending an aviation base stock with said C₂ alkylate, said hydrocodimer, said C₄ alkylate and isopentane to form high octane aviation gasoline.
- 40 4. The method in the recovery from the products of cracking of hydrocarbon oil of a fraction lighter than C₃ containing a high proportion of ethylene, which comprises subjecting the cracked hydrocarbon oil products to cooling and condensation to form a condensate consisting of cracked naphtha together with lighter normally gaseous hydrocarbons, separating uncondensed normally gaseous hydrocarbons from said condensate, subjecting said separate normally gaseous hydrocarbons to absorption with an absorption oil to absorb a portion of the said gases while the remainder passes off as tail gas, stripping the rich absorption oil to remove the absorbed normally gaseous hydrocarbons and cooling the latter to recover an absorption condensate, combining the

- 75 11. The method in the manufacture of high octane aviation gasoline which comprises recovering from the products of cracking of hydrocarbon oil a C₄ fraction containing butylenes and a C₃ and lighter condensate fraction containing a substantial proportion of ethylene and some methane, subjecting the said C₃ and lighter condensate fraction to thermal conversion at high temperature and low pressure to substantially increase the ethylene content thereof while materially reducing the C₃ content, recovering from the products of thermal conversion by condensation and absorption most of the ethylene content of said conversion products in a refrigerated condensate, fractionating said last-mentioned condensate at a pressure substantially below that required to fractionate between ethylene and methane to separate a C₂ and lighter fraction containing at least 30% by volume of ethylene and less than 25% by volume of methane and hydrogen, alkylating isobutane with ethylene of the said C₂ and lighter fraction in the presence of an aluminum halide catalyst under alkylating conditions to produce a C₂ alkylate consisting mainly of 2,3-dimethyl-butane, dividing said C₄ fraction into two portions, subjecting one portion of said C₄ fraction to polymerization and hydrogenation to form hydrocodimer from the butylene content thereof, alkylating isobutane with the other portion of said C₄ fraction in the presence of an acid alkylation catalyst to produce C₄ alkylate, and blending an aviation base stock with said C₂ alkylate, said hydrocodimer, said C₄ alkylate and isopentane to form high octane aviation gasoline.

first-mentioned cracked naphtha condensate with said absorption condensate from which tail gas has been separated, depropanizing said combined condensates to separate a C₃ and lighter fraction containing a substantial proportion of ethylene and some methane, subjecting said C₃ and lighter fraction to thermal conversion at high temperature and low pressure to substantially increase the ethylene content thereof while materially reducing the C₃ content, cooling and compressing the products of said thermal conversion and then refrigerating the compressed products to effect partial condensation thereof, separating uncondensed vapors from the resulting condensate, passing the uncondensed vapors in contact with a C₃-C₄ absorption oil produced in a subsequent step of the process to absorb most of the ethylene and separate the same from unabsorbed methane and hydrogen, passing the rich absorption oil together with last-mentioned condensate to a fractionating zone, separating a C₃-C₄ bottoms from said fractionating zone, refrigerating and recycling at least a portion of said C₃-C₄ bottoms to the absorption step to serve as the aforesaid absorption oil therein, and recovering as an overhead from said fractionating zone a C₂ and lighter fraction containing at least 30% by volume of ethylene and less than 30% by volume of methane and hydrogen.

3. The method according to claim 2, wherein said C₃-C₄ bottoms from the fractionating zone is divided, a minor proportion thereof being passed to a polymerization zone, depropanizing the resulting products of polymerization to separate a polymer bottoms containing the aromatic content from a C₃ and lighter overhead fraction, and recycling the said C₃ and lighter overhead fraction to the thermal conversion step.

4. The method in the recovery of a hydrocarbon fraction lighter than C₃ which is enriched in ethylene from cracked hydrocarbon gas condensate, which comprises separating a C₃ and lighter fraction containing a substantial proportion of ethylene and some methane from said condensate, subjecting said C₃ and lighter fraction to thermal conversion at high temperature and low pressure to substantially increase the ethylene content thereof while materially reducing the C₃ content, subjecting the products of thermal conversion to compression and refrigeration to effect partial condensation thereof, separating uncondensed vapors from the resulting condensate, passing the uncondensed vapors in contact with a C₃-C₄ absorption oil produced in a subsequent step of the process to absorb most of the ethylene and separate from unabsorbed methane and hydrogen, passing the rich absorption oil together with the last-mentioned condensate to a fractionating zone, recovering a C₃-C₄ bottoms from said fractionating zone, refrigerating and recycling at least a portion of said C₃-C₄ bottoms to the absorption step to serve as the aforesaid absorption oil therein, and separating overhead from said fractionating zone a C₂ and lighter fraction containing at least 30% by volume of ethylene and less than 30% by volume of methane and hydrogen.

5. The method according to claim 4, wherein the said C₃-C₄ bottoms from the fractionating zone is divided, a minor proportion being passed to a polymerization step, depropanizing the polymerization products to separate a polymer bottoms containing the aromatic content of said C₃-C₄ feed to the polymerization step to thereby prevent aromatic buildup in the absorption

system, also separating from said depropanizing step an overhead C₃ and lighter fraction, and recycling said overhead C₃ and lighter fraction to the thermal conversion step.

5. The method in the recovery of a C₂ and lighter fraction enriched in ethylene from a C₃ and lighter fraction of cracked gas condensate, which comprises subjecting the said C₃ and lighter fraction containing a substantial proportion of ethylene and some methane to thermal conversion at high temperature and low pressure to substantially increase the ethylene content thereof while materially reducing the C₃ content, compressing and refrigerating the products of thermal conversion to effect partial condensation thereof, subjecting remaining uncondensed vapors to absorption in a light absorption oil produced in a subsequent step of the process to absorb most of the ethylene thereof and separate from unabsorbed methane and hydrogen, combining the resulting rich absorption oil with the condensate from said partial condensation step, subjecting the mixture to fractionation to remove a C₂ and lighter fraction enriched in ethylene overhead, and refrigerating and recycling a C₃ and heavier bottoms from said fractionating step to the said absorption step to serve as the aforesaid absorption oil therein.

7. In the catalytic alkylation of isobutane with ethylene to produce an aviation blending alkylate containing a high proportion of 2,3-dimethyl butane, the improvement of utilizing refinery cracking gases containing substantial proportions of ethylene and methane as the source of the ethylene feed stock while avoiding fractionation between methane and ethylene, which comprises subjecting said refinery cracking gases to an absorption and stripping operation with the recovery of a C₃ and lighter absorption condensate enriched in ethylene and containing less than 20 volume per cent of methane and lighter, subjecting said C₃ and lighter absorption condensate to thermal conversion at high temperature and low pressure to substantially increase the ethylene content thereof while materially reducing the C₃ content, cooling and compressing the products of said thermal conversion and then refrigerating the compressed products to effect partial condensation thereof, separating uncondensed vapors from the resulting condensate, passing the uncondensed vapors in contact with a C₃ and heavier absorption oil produced in a subsequent step of the process to absorb most of the ethylene and separate the same from unabsorbed methane and hydrogen, combining the resultant rich absorption oil with said last-mentioned condensate, passing the resultant combined mixture to a fractionating zone, separating a C₃ and heavier bottoms from said fractionating zone, refrigerating and recycling at least a portion of said C₃ and heavier bottoms to the last mentioned absorption step to serve as the aforesaid absorption oil therein, also separating from said fractionating zone the overhead C₂ and lighter fraction containing at least 30 volume per cent of ethylene and less than 30 volume per cent of methane and hydrogen, and supplying said overhead C₂ and lighter fraction to the said ethylene alkylating step to serve as the ethylene-containing feed stock therefor.

8. The method in the manufacture of high octane aviation gasoline which comprises recovering from the products of cracking of hydrocarbon oil a separate C₄ fraction containing butylenes and a separate C₃ and lighter condensate

fraction containing substantial proportions each of propane, propylene, ethane and ethylene, and some methane, subjecting the said C₃ and lighter condensate fraction to thermal conversion at high temperature and low pressure to substantially increase the ethylene content thereof while materially reducing the C₃ content, recovering by condensation and absorption most of the ethylene content of said conversion products in a refrigerated condensate, fractionating said last mentioned condensate at a pressure substantially below that required to fractionate between ethylene and methane to separate a C₂ and lighter fraction containing in excess of 30% by volume of ethylene and less than 25% by volume of methane and lighter, alkylating isobutane with ethylene of the said C₂ and lighter fraction to produce a C₂ alkylate consisting mainly of 2,3-dimethyl butane, converting the butylenes of said C₄ fraction to high octane saturated paraffinic hydrocarbons within the aviation gasoline boiling range, and blending said C₂ alkylate and said C₄ high octane gasoline hydrocarbons with an aviation base stock and isopentane to produce the said high octane aviation gasoline.

Certificate of Correction

April 5, 1949.

WILLIAM E. SKELTON

It is hereby certified that errors appear in the printed specification of the above numbered patent requiring correction as follows:

Column 5, lines 43 and 44, for "precent" read *prevent*; column 15, lines 3, 4, 5 and 6, strike out

Reactor temperature, °F 4/1
Reactor pressure pounds per square inch 110
Isobutane/olefin mol ratio 275

and insert instead the following

Isobutane/olefin mol ratio 4/1
Reactor temperature, °F 110
Reactor pressure pounds per square inch 275

column 16, line 47, for "3.55 ml." read +3.55 ml.;
and that the said Letters Patent should be read with these corrections therein that the

same may conform to the record of the case in the Patent Office.

Signed and sealed this 20th day of September, A. D. 1949.

[SEAL]

JOE E. DANIELS,
Assistant Commissioner of Patents.
